UNITED STATES PATENT OFFICE

120,797

DESIGN FOR AN APPARATUS FOR SPRAYING ATOMIZED LIQUIDS

Carsten F. Boe, Wilmington, Del.

Application February 8, 1940, Serial No. 90,142

Term of patent 14 years

To all whom it may concern:

Be it known that I, Carsten F. Boe, a subject of the King of Norway, residing at Wilmington, in the county of New Castle and State of Delaware, have invented a new, original, and ornamental Design for an Apparatus for Spraying Atomized Liquids, of which the following is a specification, reference being had to the accompanying drawing, forming part thereof.

Figure 1 is a perspective view of an apparatus for spraying atomized liquids showing my design, and

Figure 2 is a top plan view thereof.

The characteristic features of the design reside in the sprayer of the configuration shown having a hemispherical top with the sprayer nozzle located in the depressed tip portion, having the specific configuration and arrangement shown.

I claim:

The ornamental design for an apparatus for spraying atomized liquids, substantially as shown and described.

CARSTEN F. BOE.
